UNITED STATES PATENT OFFICE.

RICHARD E. JONES AND VICTOR ST. CLAIR MONTEITH, OF HAGERSTOWN, MARYLAND.

ELECTROMAGNET.

1,193,793.

Specification of Letters Patent. Patented Aug. 8, 1916.

Application filed October 11, 1912. Serial No. 725,304.

To all whom it may concern:

Be it known that we, RICHARD E. JONES and VICTOR ST. CLAIR MONTEITH, residents of Hagerstown, in the county of Washington and State of Maryland, have invented 5 a new and useful Improvement in Electromagnets, of which the following is a specification.

This invention relates generally to registers and more particularly to an electrically operated register particularly adapted for use in connection with an ice chute for registering a number of cakes or blocks of ice entering the ice house or compartment, said 10 15 ice chute forming the subject matter of an application filed Aug. 26, 1912, Serial Number 713,612.

The register forming the subject matter of this invention is preferably located in the 20 office of the ice house or cold storage plant, and is operated by the opening and closing of the circuit accomplished by the passage of a cake or block of ice through the ice chute.

25 The object of our invention is to provide a register which will be highly efficient, quick in action and silent, and with these objects in view our invention consists in the novel features of construction, arrangement 30 and combination of parts hereinafter fully described, and shown in the accompanying drawings.

In the drawings forming a part of this specification, Figure 1 is a perspective view 35 of a register constructed in accordance with our invention, the actuating mechanism being covered and protected by means of a suitable casing. Fig. 2 is a detail perspective view of the register mechanism removed 40 from the casing, and Fig. 3 is a face view of the same.

In carrying out our invention we employ 45 an ordinary mechanical counter A, having an operating arm A', at one end thereof. This counter is attached in any suitable manner to a strip B, of brass or other suitable material, said strip B, being connected to the forwardly extending portion C', of the pole pieces C of the electromagnet, the 50 core D being surrounded by the requisite number of coils E of the wire, the terminals thereof extending into the circuit which contains a circuit closer the opening and closing of which serves to energize the elec-

tromagnet so that the armature plate F is 55 drawn up to the vertical pole pieces C.

The armature plate F is pivoted at G and the hanger plates H depending from the rear end of the pole pieces C and projecting forwardly from the armature plate F is the 60 finger F' to which is pivotally connected the link I, which connects the finger F' and the arm A' of the register so that at each upward movement of the armature plate the register arm will be actuated to register 65 one more number. The downward movement of the armature plate is arrested by means of a hanger bracket K, the horizontal member of which is faced with a cushion of rubber or other suitable material K' the 70 purpose of this cushion being to prevent noise and in order to prevent noise upon the upward stroke of the armature plate we arrange a strip L from one pole piece to the other at the lower forward end thereof, 75 said strip L carrying a cushion strip L' of rubber or other suitable material against which the armature plate strikes when moved upwardly and thereby preventing the same from coming into forceful contact 80 with the pole piece and making a clicking noise.

It will be noted that the depending bracket K was offset so as not to interfere with the free and easy movement of the 85 armature plate. By means of a mechanism herein shown and described we are enabled to quickly and easily actuate the register at each closing of the circuit and the operations of the various parts both in closing and 90 opening the circuit are absolutely silent. The actuating mechanism heretofore referred to is preferably contained within a metal casing M, having an opening M' through which the numbers of the register 95 can be clearly viewed. This case M is preferably constructed with supporting flanges M² by means of which it can be affixed to the wall or other fixed object.

M³ indicates openings in the top of the 100 case through which the wires leading from the coil are adapted to pass.

A register constructed as herein shown and described has been found capable of fully carrying out all the objects herebefore 105 referred to.

What we claim is:

An electromagnet comprising a core, rec-

tangular pole pieces at the core ends, a cross strip connecting said cores, an armature plate hinged at its rear side to said cores, a hanger bracket carried by the front of one 5 pole piece and acting as a stop to downward movement of the armature plate, a cushion on said bracket, a strip carried by the front edges of the pole pieces, and a cushion on

said strip, said cushion acting as a stop for upward movement of the armature, as and 10 for the purpose set forth.

RICHARD E. JONES.
V. ST. CLAIR MONTEITH.
